UNITED STATES PATENT OFFICE.

ARTHUR F. ALLEN, OF ALAMEDA, CALIFORNIA.

DESIGN FOR A HAT TREE.

Application filed March 9, 1927. Serial No. 21,073. Term of patent 14 years.

To all whom it may concern:

Be it known that I, ARTHUR F. ALLEN, a citizen of the United States, residing at the city and county of Alameda, State of California, have invented a new, original, and ornamental Design for Hat Trees, of which the following is a specification, reference being had to the accompanying drawing, forming part thereof.

Fig. 1 shows a front view of a hat tree, showing my new design.

Fig. 2 shows a side view of a hat tree, showing my new design.

I claim:

The ornamental design for a hat tree, substantially as shown.

ARTHUR F. ALLEN.
